CLAIM

The ornamental design for a weight bracelet, as shown and described.

DESCRIPTION

FIG. 1 is a top perspective view of the weight bracelet, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of a single weight of the weight bracelet, shown separately for ease of disclosure;

FIG. 10 is a perspective view of the weight bracelet, shown in a state of use with an alternate wrist band in broken lines; FIG. 11 is a perspective view of the weight bracelet, shown flat with the same band style of FIG. 10 in broken lines; and, FIG. 12 is an enlarged detail view of the weight bracelet, of the area 12 illustrated in FIG. 2.

The broken lines in the drawings illustrate the portions of the weight bracelet, which form no part of the claimed design. The dash-dot-dash broken lines encircling the enlarged views are for annotative purposes only and form no part of the claim thereof.
